W. E. CADMUS

ELECTRIC SPOTLIGHT

Filed June 28, 1922

Fig. 1

INVENTOR
WILLIAM E. CADMUS

BY
Richard & Geier
ATTORNEYS

UNITED STATES PATENT OFFICE.

WILLIAM E. CADMUS, OF BERLIN, GERMANY.

ELECTRIC SPOTLIGHT.

Application filed June 28, 1922. Serial No. 571,512.

To all whom it may concern:

Be it known that I, WILLIAM E. CADMUS, a citizen of United States of America, and resident of Berlin, Germany, have invented 5 new and useful Improvements in Electric Spotlights, of which the following is a specification.

The principal object of this invention is to provide a new and improved construction 10 of an electric spot light of the type commonly used as automobile accessories and in which the light is detachable from the customary brackets to permit the light to be moved to any desirable part of the automobile for use as a trouble finder.

Another object is to incorporate in a single compact structure or casing, the parts forming the lamp per se and a spring actuated reel upon which an extension electric 20 connecting cord is wound.

For the accomplishment of these and such further objects as will hereinafter be apparent to those skilled in the art to which this appertains, the invention consists in the 25 construction, combination and arrangement of parts herein specifically described and illustrated in the accompanying drawings, wherein is shown preferred embodiments of the invention, but it is to be understood that 30 changes, variations and modifications may be resorted to which fall within the scope of the claims hereunto appended.

In the drawings forming a portion of this specification,

35 Fig. 1 is a longitudinal cross section through a lamp embodying my invention.

Fig. 2 is a similar view of a modification, the view showing an improved or preferred construction.

40 As shown in Fig. 1, a reflector 1 is secured within an outer casing 2, the main body portion of which is of a substantially ellipsoidal form and merges at its rear portion into a handle or grip 14. Suitable 45 partitions as indicated by the reference characters 4^a and 4^b are secured to the outer casing to form a reel chamber in which the spool 4 is rotatably mounted upon the rod 15. One of the vertical faces of the reel

50 preferably the forward or front face in this embodiment is recessed to receive a torsion spring 5 one end of which is anchored to the spool and the other end is anchored to the

rod 15 in the manner common to devices of this character.

The outer end of an extension cord 6 which is wound upon the spool 4 extends through a flanged coupling member 7 which is detachably secured to the hollow bracket 8, the cord passing through bracket 8 and 60 leading to the storage battery or other source of electricity. The inner end of the extension cord 6 is secured to the spool 4 and the positive and negative wires of the cord are led through suitable holes provided in the spool flange and are anchored to conducting rings 11 set into the front vertical face of the spool. An electric socket is secured to the inner end of rod 15 and has mounted therein an electric bulb 3. Means 65 for leading the current to the bulb 3 from the extension cord comprises the conducting wires 9 connecting the socket with the spring contacts 10 which engage the contact rings 11, thus completing the circuit 75 from the cord, to the socket and lamp 3, a turn switch 12 being secured to the casing 2 and interposed in one of the wires 9.

The construction of the detachable coupling 7 permits rotation of the light about 80 a vertical axis and in a horizontal plane, while the pivotal connection 13 of the bracket 8 permits rotation of the light upon a horizontal axis and in a vertical plane, thereby providing a substantially universal 85 motion which permits the lamp to be turned to any desired position for reading road signs or to direct the light towards the edge or other part of the machine.

In the improved modification shown in 90 Fig. 2 the outer casing indicated generally by the numeral 18, preferably consists of the three interconnected sections, namely a main body or central section 19, a front or door section 20, and a rear or handle section 21. The front section 20 and rear section 21 are connected to the main or central section respectively by any suitable securing means such as a spring catch, screws, rivets or the like as indicated by the numerals 29 and 22 respectively.

An inner casing or support 26 is mounted within the outer casing 18 and comprises a front substantially cylindrical section having an annular depression or groove 28 105 formed therein to provide a seat for the

inner face of the lens 23, the outer face of which is engaged by an inwardly turned flange 20^a of the door section 20 to hold the lens 23 securely in position.

- 5 The cylindrical section 27 merges into a vertically extending wall 27^a which connects the cylindrical section 27 with a substantially frustro-conical section 30, which projects into a frustro-conical bore of the 10 spool 24 upon which the connecting cord 6 is wound. One of the inner ends of the wires comprising the cord 6 is fastened to a contact ring 31 which serves as a bearing for the front end of the spool and also connects the current from the extension cord 6 to the inner conical section 30, from which it is led to the socket 3^a by means of a small connecting wire 50.

15 The end of the other wire of the extension cord 6 is joined to a contact ring 32, secured to the spool 24 and from which the current is led by a spring contact 33 to a connecting wire 52, which leads to the socket 3^a and has a snap switch 34 interposed therein. In the modification shown in Fig. 2, the rear face of the spool 24 is recessed to provide a receptacle for the spring housing 25 in which is mounted the torsion spring 5. The spring has its outer end secured to the spool by means of a screw which is also used to attach the spring housing to the spool while the inner end of the spring is secured to the tube 35. The housing 25 is preferably constructed 20 of a pair of members 38 and 39 between which the catches 40 for controlling the length of wire unreeled are placed. Tube 35 which is rotatably mounted within the handle section 21 has at its inner end a projecting flange 35^a which bears against an inwardly turned flange 35^b of the frustro-conical section 30 to prevent longitudinal movement of the tube. The outer end of tube 35 has secured thereto a nut 37 by 25 means of which the tube may be rotated to adjust the tension of the spring 5, suitable catches being provided to prevent accidental rotation of the nut and tube. A rod 36 is threaded into nut 37 and extends the 30 tube, being connected at its front end to the socket 3^a while its rear end is provided with a knurled head for turning the screw 16 and adjusting the socket and lamp relatively to the reflector to regulate the focus 35 of the light rays. A mirror 17 is located on the holder in the commonly known way. This serves by reflection to show the driver 40 the road behind.

45 A detachable coupling such as shown in Fig. 1 is also used with the modification shown in Fig. 2, so that when it is desired to use the light as a trouble finder the coupling may be detached and the light moved to the desired place, the extension cord pulling out and unwinding the reel and the

spool 4 by means of the spring 5 taking up the slack of cord automatically as the light is replaced upon its bracket.

It will be noted that the frustro-conical section 30 shown in Fig. 2 serves as a support for the reflector 1 and also as a bearing for the front part of the spool 4, while the rear part of the spool is journaled upon the tube 35.

Having thus described my invention, what I claim as new and desire to secure by Letters Patent, is:

1. An electric spot light comprising an outer casing, and an inner casing enclosed by and secured within said outer casing, said inner casing consisting of a front portion and a rear portion, said front portion extending in juxtaposed parallel alignment with the outer casing to form a reinforced front housing, a reflector, lamp and lens mounted within said front housing, the rear portion of said inner casing being spaced from said outer casing and forming with said outer casing a rear housing, means for detachably securing said spot light to an automobile, a spring actuated reel rotatably supported by said rear portion and enclosed within said rear housing, said reel provided with a pair of contact rings, electrical connecting means between said rings and lamp, and a flexible extension cord coiled upon said reel having one of its ends extending through said outer casing to a source of electricity and its other end secured within said casing in circuit with said lamp whereby said spot light may be removed as a unit without disconnection from its source of current by withdrawal of said extension cord from said reel.

2. An electric spot light comprising an outer casing, and an inner casing enclosed by and secured within said outer casing, said inner casing consisting of a front portion and a rear portion, said front portion extending in juxtaposed parallel alignment with the outer casing to form a reinforced front housing, a reflector, lamp and lens mounted within said front housing, the rear portion of said inner casing being spaced from said outer casing and forming with said outer casing a rear housing, means for detachably securing said spot light to an automobile, a handle grip secured to said outer casing, a tube within said handle grip, a spring actuated reel rotatably mounted on said rear portion of said inner casing and tube and enclosed within said rear housing, said tube being connected to the spring of said reel and rotatable with said handle whereby the tension of said spring may be adjusted by rotation of said tube.

In testimony that I claim the foregoing as my invention I have signed my name this 2 day of June, 1920.

WILLIAM E. CADMUS.
